(57) **CLAIM**

The ornamental design for a fishing glove, as shown and described.

DESCRIPTION

FIG. 1 is a front, left and top perspective view of a fishing glove, showing my new design;

FIG. 2 is a right, rear and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view of the fishing glove, shown in a condition of use.

The broken lines showing a hand and an arm illustrate environmental subject matter and form no part of the claimed design.
